UNITED STATES PATENT OFFICE.

LOUIS LOMBARD-GERIN, OF LYONS, FRANCE.

TROLLEY FOR ELECTRICALLY-DRIVEN VEHICLES.

SPECIFICATION forming part of Letters Patent No. 656,030, dated August 14, 1900.

Application filed January 9, 1900, Serial No. 868. (No model.)

To all whom it may concern:

Be it known that I, LOUIS LOMBARD-GERIN, a citizen of the Republic of France, residing at Lyons, France, have invented certain new and useful Improvements in Automotor-Trolleys for Electrically-Driven Vehicles, of which the following is a specification.

This invention relates to an improved arrangement of automotor-trolleys for electrically-driven vehicles. This kind of trolley or current-taker is characterized by the fact that the current-collector is set in motion by its own motor independently of the vehicle (carriage, tram-car, boat, or the like) by which it is carried and to which it brings the current from the wire or supply-line by means of a flexible cable of variable length.

The arrangement of automotor-trolley which forms the object of the present invention may be employed either with continuous or with polyphase currents.

The invention is shown in the accompanying drawings.

Figure 1 is a front view of the apparatus adapted for continuous current; Fig. 2, an end view of the same; Figs. 3 and 4, similar views of the arrangement for a like apparatus for triphase current.

In Figs. 1 and 2 the metallic conductors G G', of opposite polarity, are arranged parallel one to the other. They are supported at intervals by insulated pieces mounted on posts. The automotor-trolley rests on conductors G G' by means of two contact-rollers A B, traveling on overhead wires and serving as current-takers. Their axle *a* is provided in its center with an insulation-piece. Below and parallel with the axle *a* a fixed shaft *m* is arranged, connected to the said axle by hinged rods C. The shaft *m* is also spring-mounted and carries the electromotor M, actuating the automotor-trolley. The motor M, working with triphase current, is formed of a fixed internal inductor in connection with wires conveying triphase current and an armature concentric with the inductor. The armature, the car-case of which may be, for instance, of aluminium, is mounted on the shaft *m* by the intermediary of ball-bearings. On its external surface two iron rings *d e* are mounted which actuate directly by friction rollers D E, preferably of fiber, keyed on the

axle *a* of the rollers A B, taking the current. Spiral springs suitably arranged on the hinged rods C enable the contact-pressure between the rings *d e* of the motor M and the friction-rollers D E to be suitably regulated. At the lower part of the motor M an electromagnetic brake S is arranged which has four brake-shoes *s*, which bear upon the rings *d e*, mounted on the frame of the armature. This brake has for its object to prevent the trolley running backward if it should be stopped on a gradient. A flexible cable P, extending from the automotor-trolley to the vehicle, is connected with the said trolley by a suitable joint L, preferably of the Cardan pattern. At the lower part of this suspension device or joint a sleeve I is fixed by means of a hinge *i*, which sleeve retains the end of the flexible cable P. Owing to this arrangement this cable may oscillate in all directions.

In the apparatus just described the cable P comprises the following wires under one casing: first, wires conveying continuous current to the motor of the vehicle, which current is collected by the rollers A B; secondly, wires conveying triphase current to the motor M of the trolley, which current is collected from the motor of the vehicle fed in the manner hereinafter mentioned; thirdly, wires bringing continuous current to the trolley for operating the electromagnetic brake S. The means of operating this brake must evidently be under the hand of the conductor of the vehicle. The current being discharged into the magnetic coil of the brake S, the brake-shoes *s*, which are preferably of iron, become magnetized and are pressed against the rings *d e*, which close the circuit. The shoes *s* are provided with little brass soles, forming an intermediate piece between the iron and intended to facilitate the releasing of the brakes of the shoes from the brake-rings when the current-circuit is broken.

The following is the manner in which the triphase current feeding the motor M of the trolley is collected and how a synchronism between the speed of this automotor-trolley and that of the vehicle is obtained. The motor of this vehicle is fed, as hereinbefore stated, with continuous current collected by the rollers A B of the trolley and which is conveyed by wires lodged or contained in the

flexible cable P. It is this motor which engenders the triphase current serving for operating the motor M of the trolley. For this object the motor of the vehicle is provided with three rings, connected at three suitable points selected on the winding of the armature. Three brushes bearing on the said rings collect the triphase current, which is conveyed to the motor M of the trolley by three conductors, grouped also in the casing of the cable P, as has been already stated. Under these conditions the number of phases of the triphase current collected on the motor of the vehicle being strictly proportionate to the number of revolutions which the said motor makes it is evident that the motor M will have a speed which will be itself proportionate to the speed of progression of the vehicle. The wires bringing the triphase current to the motor M reach the latter by the center of the shaft m. Thus without the intervention of the conductor a synchronism is realized which has for its consequence to render equal the speeds of the automotor-trolley and of the vehicle supplied.

It is evident that the arrangement of the automotor-trolley which has just been described may be utilized with currents requiring more than two wires for their transmission, particularly in the case of triphase current.

Figs. 3 and 4 show the means for practically carrying out the arrangement hereinbefore described when applied to triphase current. The apparatus is identically the same as that shown in Figs. 1 and 2; but it is combined with a third roller C, intended to travel along a third current-conductor G². This roller C is mounted on an axle c, located in a kind of frame in firm connection with the apparatus proper by means of springs R, which enable the said roller to rise or descend, according to the position and pitch of the upper overhead wire G². A spiral spring T serves to regulate the apparatus. Of course in order to convey to the vehicle the triphase current collected by the rollers A B C of the automotor-trolley on the overhead wires G G' G² it is necessary to have three wires, which are grouped in the flexible cable P.

It will be noticed that in the arrangement

just described the triphase current will feed, on the one hand, the motor of the vehicle and, on the other hand, the motor M of the trolley. There will be no longer a necessity of generating triphase current on the motor of the vehicle, seeing that it is triphase current itself which is distributed, and under these conditions the synchronism of the speeds of these two separate apparatuses will be found to be established by the force of circumstances.

As regards the electromagnetic brake S, it is evident that it may also be operated by means of current arising from batteries carried on the vehicle, (whether carriage, tram-car, boat, or the like.)

Having now particularly described and ascertained the nature of my said invention and in what manner the same is to be performed, I declare that what I claim is—

1. An automotor-trolley comprising an apparatus provided with a shaft having contact-rollers adapted to travel on conductors insulated one from another, the said apparatus having a motor possessing a fixed inductor and a movable armature, the periphery of which directly actuates friction-rollers on the shaft of the said contact-rollers, in combination with a flexible cable which conveys the current to the motor of the vehicle, substantially as hereinbefore described.

2. In an automotor-trolley the combination of a motor, a shaft driven thereby and carrying contact-rollers adapted to travel on insulated conductors, with a third contact-roller traveling on a third conducting-wire, the said third roller being carried by spring-rods R subject to the action of a spring T, substantially as described.

3. In an automotor-trolley, a motor having a fixed inductor and a movable armature, in combination with an electromagnetic brake adapted to act on and arrest the said movable armature, substantially as described.

In testimony whereof I have signed my name to this specification in the presence of two subscribing witnesses.

LOUIS LOMBARD-GERIN.
